UNITED STATES PATENT OFFICE.

DAVID BARRON, OF DORCHESTER, BOSTON, MASSACHUSETTS.

COPYHOLDER.

Application filed September 6, 1924. Serial No. 736,316.

To all whom it may concern:

Be it known that I, DAVID BARRON, a citizen of the United States, residing at Dorchester, Boston, in the county of Suffolk and

5 State of Massachusetts, have invented certain new and useful Improvements in Copyholders, of which the following is a specification, reference being had to the accompanying drawings.

10 This invention relates to copy holding devices and has for its object the provision of a novel glazed or glass covered frame structure within which may be held pictures, maps, papers, pamphlets, books, or the like preparatory to making photographic copies thereof, the device being designed particularly for use by commercial photographers, photo-engravers, photostat operators and the like.

15 20 An important object is the provision of a copy holder which is so constructed as to be capable of automatically adjusting itself to the thickness of the pamphlet, book, or the like held within the device so that there will be an absolute and flat contact of the copy with the glass front of the device so that rumpling, buckling, or wrinkling, of the paper or book pages will be prevented, thereby facilitating the making of accurate and unblemished photographic copies.

25 30 The invention further contemplates the provision of a device of this character embodying structural features which will constitute a great refinement in devices of this general class, the device being moreover simple and inexpensive to make, easy to use, efficient and durable in service, and a general improvement in the art.

35 40 With the above and other objects and advantages in view the invention consists in the details of construction and arrangement of parts to be hereinafter more fully described and claimed, and illustrated in the accompanying drawings, in which:

45 Figure 1 is an elevation of the device showing it in open position;

Figure 2 is a similar view showing the device in closed position and holding a book;

50 Figure 3 is an edge elevation;

Figure 4 is a cross section on the line 4-4 of Fig. 3;

Figure 5 is a longitudinal section showing the use of the book cover holding spring;

55 Figure 6 is a detail view of the spring; and

Figure 7 is a perspective view of a bracket.

Referring more particularly to the drawings, I have shown my device as comprising a main or relatively stationary frame 10 represented as being of rectangular shape 60 and of any desired size and materials. This main frame is formed as a back or board 11 formed with an opening 12. Secured to the back are hangers 13 by means of which the device may be suspended from a copy board. 65 On the front of the board or back are cleats 14.

Fitting within the opening 12 is a presser block or follower 15 which is naturally of corresponding shape and size to the opening 70 and which is provided at its rear side or face with angular brackets 16 secured thereto in any desired manner and slidably engaged on rods 17 secured to and extending rearwardly from the back 11 at opposite sides of 75 the opening 12 therein. Surrounding these rods are coil springs 18 which abut against the rear faces of the brackets 16 for the purpose of normally urging the follower or presser plate 15 forwardly with respect to 80 the back. The ends of the rods 17 projecting beyond the back are formed with heads 19 and carry washers 20 against which the springs abut.

Hinged at 21 upon the free edge of one 85 side of the stationary frame is the door or cover 22 which is of frame construction and it carries a glass pane 23. Though glass is specified, it is obvious that celluloid or other transparent material may be used if 90 desired. The glass pane 23 is of the same size as the follower or presser plate 15 so that a paper, pamphlet, book, or the like disposed on the follower plate will be engaged by the glass pane so as to permit free visibility of the copy. Suitable catches 24 are provided on the opposite side edge co-operating with catch elements 25 on the free edge of the door or cover for normally holding it 95 in closed position. 100

In the use of the device, it is of course necessary to open the door or cover 22 to permit the copy to be placed upon the follower or presser board 15 after which the door is closed and held by the catches 24. 105 It is evident that quite a large number of small pictures or the like may be mounted on the presser board or follower at the same time. It is likewise true that a book represented at B may be placed upon the follower and be held against the glass pane 23 110 in exactly the same manner as an ordinary

- sheet of paper owing to the fact that the follower or presser plate is capable of moving to a position considerably back of the rear wall 11 or back of the stationary frame. 5 This is permitted owing to the fact that the angular brackets 16 have their outer ends located rearwardly of the back.

In case the book is open at some point other than at its middle it is evident that 10 one side or portion will be thicker than the other so that there would not be proper contact of both of the exposed pages with the glass pane 23. To take care of this deficiency I make use of a bow spring 26 which is 15 adapted to be inserted between the follower or presser board 15 and the back of the book at the thinner or smaller section thereof as clearly shown in the drawings.

From the foregoing description and a 20 study of the drawings it will be readily apparent that I have thus provided a simply constructed, inexpensive and very easily used device for holding the copy of various kinds, the device having the advantage of 25 being easily capable of being hung or otherwise supported upon the copy board or other support used in connection with a camera of the type used by commercial photographers, photo-engravers, photostat operators and the like. Another distinct 30 advantage is that the copy, regardless of its nature, is so arranged that the exposed sur-

face will always be in the same plane, thereby avoiding many of the annoyances and focusing adjustments incident to the ordinary methods. 35

While I have shown and described a preferred embodiment of the invention, it should be understood that I reserve the right to make such changes in the form, construction and arrangement of parts as will not depart from the spirit of the invention or the scope of the subjoined claim. 40

Having thus described the invention, I 45 claim:

In a copy holder, a relatively stationary frame having a back wall formed with an opening, a presser board located within the opening, angular brackets secured upon the rear side of the presser board and having 50 laterally extending ends located rearwardly of the back of the stationary frame, guide rods secured to and projecting rearwardly beyond the back, said brackets being slid- 55 able on said rods, abutment elements on the outer ends of the rods, coil springs surround- ing the rods and engaging said abut- ment elements and the brackets, and a door for closing the front of the frame, the door having a transparent panel therein of a size 60 to engage upon the presser board.

In testimony whereof I hereunto affix my signature.

DAVID BARRON.
